UNITED STATES PATENT OFFICE.

ANTONIO SCARPITTO, OF RICHMOND, VIRGINIA.

GRATING-MACHINE.

1,188,328.

Specification of Letters Patent. Patented June 20, 1916.

Application filed March 29, 1916. Serial No. 87,583.

To all whom it may concern:

Be it known that I, ANTONIO SCARPITTO, a citizen of the United States, and a resident of Richmond, in the county of Henrico and State of Virginia, have invented a new and useful Improvement in Grating-Machines, of which the following is a specification.

My invention is an improvement in grating machines, and has for its object to provide a machine especially adapted for grating horseradish and other pungent materials, wherein a support is provided for a grating wheel having a discharge chute below the wheel, and an inner inclosing hood above the wheel having an opening at one side of the wheel for permitting access thereto, and an outer inclosed hood inclosing the inner hood and having an opening 10 registering with the opening of the inner hood, and having an outlet at the opposite side, together with exhausting apparatus connected with the outlet to remove the pungent odors without affecting the grated material.

In the drawings: Figure 1 is a perspective view of the improved machine, Fig. 2 is a longitudinal vertical section, and Fig. 3 is a section on the line 3—3 of Fig. 2. The present embodiment of the invention 20 comprises a table 1, having supporting legs 2 and provided with an opening 3 in which is arranged a grating wheel 4, the said wheel being secured to the shaft 5, which 30 is journaled in bearings on the table. The outer end of the shaft 5 is provided with fast and loose pulleys 6 and 7, and a discharge chute 8 is connected with the table below the opening 3.

An inner hood 9 is connected with the table above the opening 3 and inclosing the same, the said hood being curved transversely to correspond with the periphery of the wheel, and this hood has an opening 40 10 at the front thereof, to permit access to the wheel. An outer inclosing hood 11 is also provided, the said hood inclosing the inner hood, and the front of the hood 11 is open and is normally closed by a door 12 which 50 is hinged at the top of the hood at 13 to permit the door to be opened and closed.

The door 12 is provided with an opening 14 at its lower edge, registering with the opening 10 of the inner hood, and through 60 these registering openings 10 and 14, the

material to be grated may be fed to the wheel.

The outer inclosing hood is provided with a nipple 15 at the opposite side from the door, and a discharge pipe 16 leads 60 from the nipple to the casing 17 of an exhaust fan. The discharge pipe 16 opens into the fan casing 17 axially, and the shaft 18 of the fan is extended at the opposite side from the tube 16, and is provided with 65 a pulley 19 for connection with a suitable driving shaft 20. This shaft 20 is journaled in bearing arms 21, on a fixed support, and is provided with pulleys 22 and 23 which are connected by belts 24 and 25 with the 70 pulleys 6—7 and 19 respectively. The discharge chute 26 of the fan casing extends from the said casing to a suitable point of discharge, as for instance, through the wall of the room wherein the grating machine 75 is arranged, delivering outside of the room or building. The table top 1 is extended at the front of the outer hood or inclosing casing, as shown more particularly in Fig. 1, the said extension being at the opening 80 14. The table 1 is sufficiently elevated to permit a small car 27, upon which is mounted a suitable container 28 for the grated material, to be placed under the table, the open top of the container being directly below the chute 8.

In operation, the material to be grated, as for instance horseradish, is fed through the openings 10—14 into contact with the periphery of the rotating wheel. The 90 grated material falls through the chute 8 into the container 28, and the pungent odors given out during the grating operation, enter the outer inclosing hood 11 and are drawn away and discharged where they 95 will not be offensive, by means of the exhausting device 17. The door 12 gives free access to the interior of the casing 11, and the inner inclosing hood 9 is preferably made detachable, to permit access to the 100 grating wheel.

I claim:

1. A grating machine comprising a table having an opening, a grating wheel journaled in the opening, the table having a discharge chute below the opening, an inner hood inclosing the wheel above the opening, an outer hood or casing inclosing the inner hood, said hoods having registering openings at one side of the table for permitting 110

access to the wheel and the outer hood having an outlet at the opposite side from the openings, exhausting mechanism connected with the outlet, and a common means for rotating the wheel and for driving the exhausting mechanism.

2. A grating machine comprising a supporting table having an opening, a grating wheel journaled in the opening, inner and outer hoods inclosing the wheel and hav-

ing registering openings at one side for permitting access to the wheel, and exhausting mechanism connected with the outer hood for withdrawing offensive odors from the hood and discharging them away from the machine.
